UNITED STATES PATENT OFFICE.

JOHN T. WALKER, OF NORMAN, OKLAHOMA TERRITORY.

PUMP.

SPECIFICATION forming part of Letters Patent No. 664,069, dated December 18, 1900.

Application filed July 1, 1899. Serial No. 722,544. (No model.)

To all whom it may concern:

Be it known that I, JOHN T. WALKER, a citizen of the United States, residing at Norman, in the county of Cleveland and Territory of Oklahoma, have invented certain new and useful Improvements in Pumps, of which the following is a specification.

My invention is an improved water-pump.

The particular advantage claimed by me for this pump is that it throws a continuous stream of water to any height within the power of the pump. The pump has six ball-valves and two cylinders, two valves in each of the cylinders. These cylinders terminate in two tapering or cone-shaped pipes, the upper ends gradually tapering into a single pipe. These two upper cone-shaped parts 5 and 6 have each a ball-valve.

The pump may be operated either by crank 20 or lever power.

The operating attachment is adjustable and may be lowered or raised to suit the convenience of the operator or conditions.

This pump may be used under ground in mines and other like places, in which case the top or upper end of the pump can be above ground. By attaching a hose to the pump it may be used to force water to a great height.

30 My invention is described as follows:

Figure 1 is an elevation of my invention. Fig. 2 is a view showing one of the cylinders and the pipes in section, the head and framework for operating the beam being shown in 35 perspective.

1 represents the head of the pump. The head of the pump is hollow and is provided with a cap 2, which is screwed on. This cap may be screwed off, and rubber tubing or 40 any kind of piping may be attached to the threaded neck. 3 is the nozzle, which may also be provided with a cap to fit closely thereon when the water is intended to be sent out through the neck of the head.

45 Extending from the head downwardly to any desired distance is a pipe 4. This pipe 4 has attached to its lower end two diverging cone-shaped pipes 5 and 6. To the lower ends of these two diverging cone-shaped

50 pipes are secured two lower cylinders 7 and 8, respectively. The lower ends of these cylinders 7 and 8 are closed by heads 10, each

being provided with a valve-seat 11, and in each one of these valve-seats rests a ball-valve 12, and to the lower ends of each of these heads 10 are secured loops 9 to prevent large pieces of foreign matter from entering into the pump. In each one of these cylinders 7 and 8 and near their lower ends is situated a moving cup-piston 13. Said cup-pistons are 60 each provided with a ball-valve 15, and over the top of each cup-piston is a strip 16 to keep the ball-valve from working out. In each of the diverging cone-shaped pipes 5 and 6 is a rod 17, and under these rods is situated a 65 ball-valve 18. Secured to each of the cup-pistons 13 is a rod 19, extending upwardly and through an opening 20 in the upper ends of the said cylinders 7 and 8. These rods extend through the platform or disk 21, which 70 is attached to the pipe 4 at a point which is supposed to be above the ground.

Secured to the pipe 4 above the disk 21 is the operating mechanism, which is constructed substantially as follows: Two bands 22, 75 one above the other, are brought around the pipe 4 and secured thereto by tightening the bands by means of bolts and nuts or by any other known mechanical device. These bands 22 are each provided with arms 23. These 80 arms are provided with perforations 24, and between these arms and running vertically are secured two uprights 25, making a rectangular framework, and to the upper end of this rectangular framework is secured a cross-beam 26, which acts as a bearing for gearing-wheels. This cross-beam 26 is properly braced by braces 27, and to this beam 26 are journaled three cog-wheels 28, 29, and 30. Underneath this beam 26 and some little distance from the same is hinged a walking-beam 31. This walking-beam is provided with bolts or bearings 32 and 33. To the axle of the center cog-wheel 29 is secured a crank-handle 34, which is used to operate said wheel. Near 95 the periphery of each wheel is a pin 35, and to each of these pins is pivoted the upper end of a rod 36, the lower ends of which are pivoted to the bearings 32 and 33, and to these bearings 32 and 33 are pivoted the upper ends 100 of the rods 19.

The operation is as follows: The three wheels 28, 29, and 30 mesh with each other. The operator takes hold of the crank-handle

and turns the center wheel. This operation turns the other two wheels, which has the effect of moving one rod up and the other rod down alternately, which operates the cup-pistons 13, by which means the water is forced upward through the pipe 4.

Having described my invention, what I claim as new, and desire to secure by Letters Patent, is—

10. A water-pump, consisting of the main pipe, two diverging pipes, provided with valves and valve-seats; cylinders, secured to the lower ends of said diverging pipes, also provided with valves and valve-seats and cup-pistons, substantially as described; adjustable bands, encircling the main pipe, and having arms extending therefrom; uprights, secured to said arms; a cross-beam secured to said uprights; a walking-beam hinged between said uprights; cog-wheels, journaled to said cross-beam and meshing with each other; two pit-

men, the upper end of one pivoted to one outer cog-wheel, its lower end to the corresponding end of the walking-beam, the upper end of the other arm, pivoted to the other outer cog-wheel, its lower end to the corresponding end of said walking-beam; two rods, their upper ends pivoted, one to each end of said walking-beam, their lower ends extending into the cylinders and secured, one to each of said 30 cup-pistons, said cog-wheels adapted to be operated by a crank-handle or other suitable means, and thereby operate said walking-beam, said rods and said cup-pistons, substantially as shown and described and for the 35 purposes set forth.

In testimony whereof I affix my signature in presence of two witnesses.

JOHN T. WALKER.

Witnesses:

JOHN FRANING,
W. H. SEAWELL.
